BRIDLE ATTACHMENT

Wayne B. Stephens, Hollywood, Calif.

Application May 1, 1933, Serial No. 668,842

2 Claims. (Cl. 54—6)

This invention relates to an improved bridle for horses.

One object of the invention is to provide a bridle which will be humane and which will, nevertheless, be very effective.

A further object of the invention is to provide a bridle having means for controlling a horse which, when placed in proper position, will not become disengaged or disarranged from about the horse's mouth.

A further object of the invention is to provide a device of this character wherein the nose band employed will be shielded along its inner surface so that scratching of the horse's nose and consequent irritation will be prevented.

And a still further object of the invention is to provide a bridle which may be easily assembled any may be placed into use with the utmost facility.

Other and incidental objects of the invention, not mentioned in the foregoing, will be apparent during the course of the following description.

In the drawing forming a part of my application, Figure 1 is a perspective view showing my device as it would appear applied to a horse,

Figure 2 is an enlarged perspective view of the device itself, and

Figure 3 is an enlarged fragmentary vertical sectional view taken on the line 3—3 of Figure 2 and looking in the direction indicated by the arrows.

Referring now more particularly to the accompanying drawing wherein like numerals designate similar parts throughout the several views, the numeral 1 indicates, in general, a bridle for a horse. The bridle comprises a brow band 2, a crown piece 3, a throat latch 4 and cheek straps 5. The brow band, crown piece, throat latch, and cheek straps are connected at opposite sides of the horse's head by means of rings 6.

Mounted at the corresponding lower ends of the cheek straps 5 is my improved attachment which includes side pieces 7 and 8 which are preferably formed of flat strips of metal which are light in weight but of sufficient strength to prevent bending or buckling. The corresponding upper ends of the side pieces 7 and 8 are formed with curved portions 9 and 10. Carried on the corresponding free ends of the curved portions are hooks 11 and 12. As seen in Figure 1 of the drawing, the side pieces are adapted to be disposed adjacent the horse's mouth at opposite sides thereof with the curved portions 9 and 10 disposed rearwardly.

A small chain 13 is disposed beneath the horse's jaw and has its opposite ends connected with the hooks 11 and 12. The chain 13 cooperates with the side pieces 7 and 8 for retaining said side pieces in a substantially vertical position. It is to be understood that the chain 13 may be substituted by a strap, if desired, or said chain may, if desired, be provided with a leather sheath so that the metal will not come in contact with the horse's jaw. Carried on the chain 13 and adapted for positioning medially of its length is a ring 36.

Mounted on the side pieces 7 and 8, at the base of the curved portion, and in a substantially horizontal plane with the hooks 11 and 12, are loops 14 and 15 which are preferably formed of heavy wire and are riveted, or otherwise secured, to the inner margin of the side pieces. The loops 14 and 15 are adapted to receive the straps of a rein 16. Carried on the lower end portion of the side pieces 7 and 8 are eyes 17 and 18 and freely mounted in the eyes are rings 19 and 20 which are adapted securely to receive the reins 21 and 22. Carried on the side pieces 7 and 8 and riveted, or otherwise secured, thereto at points substantially medially between loops 14 and 17 on the piece 7, and 15 and 18 on the piece 8, are loops 23 and 24. Extending between the loops 23 and 24 and adapted to engage beneath the horse's lower jaw is a preferably leather strap 25, said strap 25 extending through the ring 36. The strap 25 is adjustable by means of a buckle 26.

Mounted on the side pieces 7 and 8, near the bases of the curved portions 9 and 10, are connecting plates 27 and 28. The connecting plates 27 and 28 are preferably formed of flat metal and are slightly bowed longitudinally. As best seen in Figure 3 of the drawing, the lower end portions of the connecting plates 27 and 28 are swingingly connected to the curved portions by means of screws 29 which are upset at their inner ends, as indicated at 30 so that the plates may be permitted to swing on the curved portions without danger of loosening the screws. Mounted on the connecting plates, near their corresponding inner ends, are loops 31 and 32 which are adapted to receive the cheek straps 5 at opposite sides of the horse's head. The loops 31 and 32 may be riveted or otherwise secured to the plates 27 and 28.

Preferably riveted to the plates 27 and 28 is an arcuate nose band 33 and the nose band is formed from sheet metal. Riveted to the inner surface of the nose band is a leather, or other relatively soft lining piece 34 which will protect

the horse's nose from direct contact with the metal of the nose band. A pair of rivets 35 are employed for connecting the opposite ends of the nose band with the upper corresponding ends of the connecting plates 27 and 28. If desired, the nose band 33 may be substituted by a chain sheathed in a leather covering.

In use, a bridle equipped with my improved device is placed upon the horse's head and the reins are connected to the loops 14 and 17 on the side piece 7, and 15 and 18 on the side piece 8. The strap 25 and the chain 13 are disposed beneath the horse's chin groove immediately rearwardly of the horse's lower jaw. When driving the horse, the tension upon the reins at either side will tighten or loosen the tension of the strap 25 and chain 13 against the horse's chin groove, and at the same time, the tension of the nose band 33 against the horse's nose will be varied. Therefore, the movements of the horse may be readily and positively controlled by varying the stress placed upon the reins, as above explained. It is pointed out that the use of my improved bridle attachment will eliminate the inhumane use of the bit in the horse's mouth. My bridle will be particularly useful in connection with horses and mules having tender mouths. The device is especially adapted for use on polo horses where it is otherwise necessary to use bits a great deal.

Attention is directed to the fact that my improved attachment may be used with any standard bridle, the one shown herewith being used merely for purposes of illustration.

The parts of my improved attachment are so located that the nose band will be disposed in a position on the horse's nose to permit perfect balance and greater leverage so that the chain 13 and strap 25 will be disposed in the chin groove of the horse's jaw.

My improved attachment will be easy to install and will be cheap in manufacture and it is believed that a reading of the foregoing description will make clear the fact that I have provided a highly efficient device of this character.

Having thus described my invention, I claim:

1. In a device of the character described, side pieces each consisting of a flat strip of rigid material having its upper portion rearwardly and downwardly bent, hooks carried by the lower free ends of the curved upper portions of said strips and depending therefrom, eyes pivoted to the lower ends of said strips and extending rearwardly therefrom, rings carried by said eyes for engagement by a lower set of reins, upper and lower loops carried by said strips in spaced relation to each other longitudinally thereof with the upper loops in approximately the horizontal plane of said hooks and the lower loops intermediate the eyes and upper loops, the said upper loops constituting attaching means for upper reins, a resilient nose band, connecting strips secured at their upper ends to ends of said nose band and extending longitudinally therefrom in alinement with the band and having their lower ends pivoted to said side strips at approximately the forward ends of the curved upper portions of the said side strips, loops carried by said connecting strips intermediate their ends for engagement by cheek straps of a bridle, a chain suspended at its ends from said hooks and of a length to be disposed in a horse's chin groove, a ring loose upon said chain and normally disposed centrally thereof, and a strap passed loosely through the ring of said chain and at its ends connected with the lower loops of the side strips.

2. A curb comprising a pair of cheek bars, a chin strap extending loosely between intermediate portions of the cheek bars, a jaw chain extending loosely between the upper end portions of the cheek bars, means connecting the jaw chain, at an intermediate point, to the chin strap, arms pivotally mounted on the cheek bars in spaced relation below the upper ends thereof, and a nose band extending between the free end portions of the arms.

WAYNE B. STEPHENS.
